CORSET.

(Application filed Apr. 10, 1901.)

(No Model.)

UNITED STATES PATENT OFFICE.

ANNIE E. DECKER, OF BROOKLYN, NEW YORK.

CORSET.

SPECIFICATION forming part of Letters Patent No. 696,227, dated March 25, 1902.

Application filed April 10, 1901. Serial No. 55,123. (No model.)

To all whom it may concern:

Be it known that I, ANNIE E. DECKER, a citizen of the United States, residing in the borough of Brooklyn, county of Kings, and 5 city and State of New York, have invented certain new and useful Improvements in Corsets, of which the following is a specification.

This invention relates to corsets made up from pieces of woven fabric cut to the proper 10 shape and stitched together to impart the desired contour to the corset. In this class of corsets, in order that they may mold themselves to the form of the wearer, gores are set in at both top and bottom; and one of the 15 features of this corset is the arrangement of the "grain" of the fabric so that the warp or weft threads will extend straight or practically straight with or along the upper and lower margins of the corset and not be oblique 20 to or "bias" with said edges. This avoids that stretching of the goods which produces a change in the shape and fit of the corset.

Another feature of importance is a provision 25 for adjusting the compass of the corset at its upper edge, and particularly in front, in order to cause the corset to fit snugly over the bust.

In the drawings which serve to illustrate 30 an embodiment of the invention, Figure 1 is a view of the corset as a whole distended to fit the person of the wearer, the view being in substance a front view. Fig. 2 is an inside view of the front upper edge of the corset, showing the adjusting feature; and Fig. 3 is a plan view of the part seen in Fig. 2. 35 These views are on a somewhat larger scale than Fig. 1.

As in the ordinary corset, the one herein 40 illustrated comprises two like halves A A, of which a a are the busks, provided with any suitable fastenings, and b the lacing at the back. The lines of stitching indicate the 45 pockets containing the bones. At the top of the corset in front are gores c, and at the bottom are hip-gores d and larger front gores e. The gores have the directions of the threads of the fabric marked on them, and it should

be understood that the threads comprising the main fabric of the corset will also extend in the same directions. As the strains on the 50 fabric of the corset tend to enlarge or distend it or to stretch the upper and lower edges thereof, it will be seen that the peculiar arrangement of the threads in the fabric, as herein shown, serves to transmit the strain 55 on the transverse threads of the fabric longitudinally thereof or in the direction which enables them to resist the strains best. Therefore the corset will maintain its form and dimensions very perfectly and for a long time. 60

At the upper edge of the corset, at each side of the busks and extending over the space of the two gores c, is a pocket g, in which is a double draw-string h, one end of which is fixed at z and the other end of which passes 65 out of the pocket at the edge thereof where the busk is situated. This free end or bight of the string or cord h is (or may be) provided with an eye i to engage a hook j, secured to the corset at the opposite side. Figs. 2 and 70 3 clearly show the arrangement. There may, if desired, be a series of two or more hooks j, set at different distances from the busk, so that the draw-strings may be made to gather and take in more or less of the front 75 of the corset at its upper edge, the hooks serving to hold all that has been taken up. In Figs. 2 and 3 only a part of each pocket is shown and only the hooks j at the points between the gores c. 80

Having thus described my invention, I claim—

A corset having at its upper edge in front the pockets g, the draw-strings h, fixed at one end in the respective pockets, and the engaging hooks on the corset, substantially as and for the purpose set forth. 85

In witness whereof I have hereunto signed my name, this 8th day of April, 1901, in the presence of two subscribing witnesses.

ANNIE E. DECKER.
